UNITED STATES PATENT OFFICE.

ALFRED T. KRUSE, OF DEFIANCE, OHIO, ASSIGNOR TO AMERICAN STEEL PACKAGE COMPANY,
OF DEFIANCE, OHIO, A CORPORATION OF OHIO.

SHEET-METAL PACKING-CASE.

No. 872,998.

Specification of Letters Patent.

Patented Dec. 3, 1907.

Application filed September 5, 1906. Serial No. 333,286.

To all whom it may concern:

Be it known that I, ALFRED T. KRUSE, a citizen of the United States, residing at Defiance, in the county of Defiance and State of Ohio, have invented certain new and useful Improvements in Sheet-Metal Packing-Cases, of which the following is a specification.

My invention relates to improvements in sheet-metal packing-cases especially designed for the transportation and storage of liquids contained in bottles and similar vessels.

The invention relates to that class of sheet-metal packing-cases which are without a closed bottom and also to that class known as "stacking-cases",—that is,—the bottles or containing vessels in the compartments or cells are supported by means of a series of supporting-bars interposed between and secured to the lower portions of the sides and ends of the case, and said sides and ends are tapered or inclined so that the cases may be "stacked" one above the other, the beading formed about the lower edges of the sides and ends of the case being adapted to take over the beading formed about the upper edges of the case upon which it is stacked or supported.

The paramount object of the invention is to produce a generally improved case of this class which will be simple in construction, cheap of manufacture, durable in use, and much better adapted to its intended purposes than any other invention of the same class with which I am acquainted.

Another object is to provide a series of supporting-bars for bottles to be used in conjunction with sheet-metal partitions or divisions preferably constructed like those disclosed in Patent No. 805,424, issued to me Nov. 21, 1905, and which will not only tend to strengthen and support the lower edges of the sides and ends to which it is attached, but, by reason of the construction, herein shown and described, be better adapted to support the case with its contents upon the ordinary conveyer now in common use by brewers and form a convenient bearing-surface for the same.

With these ends in view, the invention consists in the novel construction, arrangement and combination of parts, hereinafter described, illustrated in the accompanying drawings, and particularly pointed out in the appended claims.

Referring to the drawings, forming a part of this specification, Figure 1, is a transverse sectional view of a packing-case constructed in accordance with my invention. Fig. 2, a longitudinal sectional view of the lower portion of the case. Fig. 3, a horizontal sectional view taken through line 3—3, of Fig. 1. Fig. 4, a detail perspective view of one end of one of the supporting-bars secured to the walls of the lower portion of the case. Fig. 5, a detail perspective view showing relative position of the main cross supporting-bar and one of the series of supporting-bars intersecting the same. Fig. 6, a similar view showing middle portion of the main cross supporting-bar.

Similar characters of reference designate like parts throughout all the figures of the drawings.

The improved case is preferably made up of side and end walls 1, and 2, suitably secured at the corners of the case and, preferably, provided with a series of strengthening-ribs 3.

The upper and lower edges of the sides and ends are bent over and about forming a beading 4, and, preferably, inclosing a wire 5, and near said beading 4, the said sides and ends are bent or crimped to form a continuous or encircling inwardly - extending strengthening-flange or ledge 6, adapted to contain a flat reinforcing strengthening-bar or iron 7, extending longitudinally about the said sides and ends as shown most clearly in Fig. 3, of the drawings.

The upper strengthening-flange or ledge forms a lid-supporting-flange taking under the beaded or marginal edges of the lid or cover 8, and the lower flange or ledge forms a bottom-supporting-flange adapted to rest upon the upper edges or beading of the sides and ends of the case upon which the case is stacked, and also taking under and supporting the ends of a series of supporting-bars to be hereinafter described.

The sheet-metal partitions or divisions 9, are mounted and interposed between the sides and ends and secured thereto in any suitable and convenient manner.

A series of supporting-bars 10, of any suitable and convenient form, but, preferably, of substantially T-shape in cross-section, as shown, are formed, in the present instance, out of sheet metal and are adapted to take under and support the bottles or containing

vessels arranged in the cells provided by said partitions 9, mounted above.

The T-shaped supporting-bars 10, are supported, intermediate the ends thereof, by 5 intersecting a main or cross supporting-bar 11, interposed between the sides of the case, and the latter is preferably secured thereto by means of tongues 12, (see Fig. 5) taking through vertical openings or slots and bent 10 over the outer sides of the case, in the same manner as are secured the cross sheet-metal partitions or divisions 9. The ends of the supporting-bars 10, are provided with tongues 10^a, which take through slots in the walls of 15 the case, and are bent over the outer sides of the case.

The lower or depending portion of the T-supporting-bars has its ends cut away to afford a notch or recess 13, to receive and 20 take over the lower inwardly-extending flange 6, of the case, and the beading at the upper edge of the case upon which it is stacked. It will also be observed that the lower edges of said depending portion of the 25 supporting-bars are flush with the lower edges or beading of the sides and ends of the case thus giving further support and strength to the various parts of the case and providing a friction-bearing surface for engagement with the conveyer. The supporting-bars when cut away at the ends to afford a notch or recess to take over the flange 6, are, preferably, secured thereto by means of rivets 13^a, but the bars 10, may be of any 30 suitable form and secured and supported directly to the walls of the case, without the intervention of a flange, by means of the tongues 10^a, or the ends thereof may take into a recess formed by an outwardly-extended 35 flange (not shown) similar to flange 6, and not provided with a strengthening bar or iron 7.

Having thus described my invention, without having attempted to set forth all 45 the forms in which it may be made, or all the modes of its use, I declare that what I claim and desire to secure by Letters Patent is,—

1. In a packing-case, inclined sides and ends bent to form continuous lid and bottom-supporting-flanges and a beading at the 50 upper and lower edges of said sides and ends, a plurality of supporting-bars having their ends mounted on said bottom-supporting-flange, and a reinforcing-iron mounted within said flanges.

2. A packing-case, comprising sides and ends bent to form continuous lid and bottom-supporting-flanges and a beading at the upper and lower edges of said sides and ends, 55 a beaded cover mounted on said lid-supporting-flange, and a series of supporting-bars mounted on said bottom-supporting-flange.

3. A packing-case, comprising sides and ends crimped to form lid and bottom-supporting-flanges and a beading at the upper 60

and lower edges of said sides and ends, a beaded cover mounted on said lid-supporting-flange and within the upper beading of the case, a series of supporting-bars having the ends thereof taking over and resting on 70 said bottom-supporting-flange, and a main cross supporting-bar intersected by said series of supporting-bars.

4. A packing-case, comprising inclined sides and ends crimped to form encircling lid 75 and bottom-supporting-flanges, and an upper and lower beading about the edges of said sides and ends, a lid or cover mounted on said lid-supporting-flange, a series of supporting-bars provided with notched ends 80 taking over and resting on said bottom-supporting-flange, and a cross supporting-bar engaging and supporting the intermediate portions of said supporting-bars.

5. In a packing-case, the combination 85 with sides and ends provided with a reinforced bottom-supporting-flange and a beading about the lower edges of said sides and ends; of a series of supporting-bars mounted on said flange and flush with said beading. 90

6. In a packing-case, the combination with sides and ends provided with a reinforced bottom-supporting-flange and a beading about the lower edges of said sides and ends; of a series of supporting-bars mounted 95 on said flange, and a cross supporting-bar engaging and supporting the intermediate portions of said bars.

7. In a packing-case, the combination with sides and ends bent to form a bottom- 10 supporting-flange, a series of partitions mounted therein, and a cross supporting-bar; of a series of supporting-bars intersecting said cross supporting-bar and having their ends resting on said bottom-supporting-flange.

8. In a packing-case, the combination with the walls of the case provided with a bottom-supporting flange and a beading adjacent thereto, and a cross supporting-bar; 11 of a series of T-shaped supporting-bars intersecting said cross supporting-bar and having their depending portions flush with said beading.

9. In a packing-case, a case body carrying 11 a series of partitions forming a series of bottle-cells and an open bottom comprising a cross supporting-bar provided with openings and a series of bottle-supporting-bars intersecting said cross supporting-bar through 12 said openings.

10. In a packing-case, a case body carrying a series of partitions forming a series of bottle cells, and an open bottom consisting of a series of bottle-supporting-bars mounted 13 beneath said bottle cells, and a cross supporting-bar engaging and supporting said bottle-supporting-bars.

11. In an open bottom packing-case, the combination with suitable walls, a series of 14

partitions mounted therein and providing
bottle cells; of an open bottom consisting of
a main cross supporting-bar, and a series of
supporting-bars intersecting said cross sup-
5 porting-bar and adapted to take under and
support the bottles mounted in said bottle
cells.

In testimony whereof I have signed my
name to this specification in the presence of
two subscribing witnesses.

ALFRED T. KRUSE.
